UNITED STATES PATENT OFFICE.

CHARLES E. BROADWELL, OF SAN FRANCISCO, CALIFORNIA.

LEAF FOR LOOSE-LEAF LEDGERS.

No. 839,718.

Specification of Letters Patent.

Patented Dec. 25, 1906.

Application filed March 1, 1906. Serial No. 303,610.

To all whom it may concern:

Be it known that I, CHARLES E. BROADWELL, a citizen of the United States, residing in the city and county of San Francisco, State of California, have invented certain new and useful Improvements in Leaves for Loose-Leaf Ledgers; and I hereby declare the following to be a full, clear, and exact description of the same.

10 The present invention relates to an improved leaf for use in connection with what is known as "loose-leaf ledgers," "temporary binders," and "transfer-binders," the object of the invention being to so construct the 15 leaves that the surface of one leaf will interlock, so to speak, with the surface of its opposing leaf, thereby preventing the leaves crawling, creeping, or slipping outward during the opening of the book while being handled.

Books of the loose-leaf type are generally of large size and of considerable weight, containing five hundred or more pages. The stub of each leaf is formed with spaced slotted perforations, which perforations enable the leaves to be fitted over the fixed filing-posts of the book, which posts are designed to hold the leaves in adjusted position. However, practical use of such books has 25 demonstrated the fact that when the heavy books are opened the stubs, due to the weight of the leaves and binding of the book acting as a lever, tend to and as a matter of fact do cause the leaves to crawl or creep outward, 30 the leaves being thus forced away from the filing-posts of the book. It is this defect which the present invention is designed to overcome.

40 To comprehend the invention, reference should be had to the accompanying sheet of drawings, wherein—

Figure 1 is a transverse sectional view of an ordinary loose-leaf binder, said view disclosing the arrangement of the leaves therein. 45 Fig. 2 is a broken plan view of one of the leaves. Fig. 3 is a transverse section taken on line xx , Fig. 2 of the drawings; and Fig. 4 is a longitudinal section disclosing a modification of the leaf set forth in Fig. 2 of the 50 drawings.

Referring to Fig. 1 of the drawings, the numerals 1 and 2 designate the front and back cover, respectively, of an ordinary book of the loose-leaf type, and 3 the spaced filing-posts, which usually are rigid with the back cover 2 of the book. The sheets 4 are formed

with the usual spaced perforations 5, which enable the sheets being fitted upon the filing-posts 3, said perforations being formed in the stub 6 of the sheets 4. Each stub is slotted 60 longitudinally, as shown at 7, which slots intercept the perforations of the sheets. It is by reason of the stubs being thus slotted that any given sheet may be withdrawn or removed from within the book. 65

The foregoing is the usual construction of leaves used in connection with books of the loose-leaf type.

To prevent the crawling or creeping of the leaves during the handling of the books, the 70 leaves to be used are so formed that the surface of one leaf will interlock with the surface of an adjacent leaf, so that all the leaves after being fitted upon the filing-posts and held between the covers of the book will be 75 held locked independent of the frictional hold of the leaf to the filing-posts of the book. A simple, effective, and inexpensive means of so interlocking the sheets or leaves is to emboss the stub-section 6 of each sheet 4 so as 80 to form one or more raised projections 8 on the upper surface thereof, whereby the under surface of each stub is provided with one or more depressions 9, so that when the sheets or leaves are fitted within the book the raised 85 projections of one stub will register with and fit into the depressions of the sheet immediately above, the sheets or leaves of the book being thus interlocked one with the other.

90 Preferably the projections 8 are formed intermediate the perforations 5 of the stub 6; but this is an immaterial feature. The simplest manner of forming the projections 8 is by embossing the stubs of each sheet, the depressions 9 being thus formed as the under 95 surface of the projections 8. In so embossing the stub of the sheet or leaf the said stub preferably should be slightly damped. The shape of the projection 8 may be varied as desired, the only requirement being that a 100 resisting-surface against slippage of one leaf from the other be provided when the sheets or leaves are interlocked.

105 It is obvious that the interlocking of the sheets may be accomplished other than by the formation of projections on one face of the stub of the leaf and depressions on the opposite face, for, as disclosed by Fig. 4 of the drawings, the stub of each leaf may be corrugated or fluted transversely. In such 110 case the upper surface of the stub presents a series of transverse ridges 10 and the under

surface, a series of transverse depressions or grooves 11, the ridges of one surface of the stub interlocking with the grooves or depressions on the surface of the adjacent stub of the leaf immediately thereabove.

While only depressions and projections and transverse ridges and grooves have been illustrated as the engaging means for holding the stub of one leaf locked to the opposing stub of an adjacent sheet, it is obvious that any engaging surface for the leaf-stub may be equally as well employed to hold the parts locked one to the other. Consequently the intent is to cover, broadly, leaves for loose-leaf books having engaging surfaces for locking one leaf to an adjacent leaf of the book.

By the expression "loose-leaf book" as used herein is meant any form of binder for the holding of loose leaves.

Having thus described the invention, what is claimed as new, and desired to be protected by Letters Patent, is—

1. A leaf for loose-leaf books, the stub portion thereof having its surfaces formed to interlock with the stub-surfaces of adjacent leaves of a book.

2. A leaf for loose-leaf books, the stub portion thereof being formed with projections on one face and depressions on the opposing face, so that the leaf will interlock with the surfaces of adjacent leaves of a book.

3. A leaf for loose-leaf books, the surfaces thereof provided at the binding edge thereof with engaging means for interlocking with the surfaces of adjacent leaves of a book, the

other portion of the surface of the leaf being free and unobstructed.

4. A loose-leaf book provided with a series of leaves, the surfaces of each leaf interlocking with the surface of adjacent leaves of the book at points in alignment with and intermediate the binding-points of the leaves.

5. A leaf for loose-leaf books, the same being provided with a stub-section, the surfaces of said section being formed to interlock with the surface of stub-section of adjacent leaves of a book.

6. A leaf for loose-leaf books including a stub portion or binding edge, openings therein for engagement with filing-posts, and means intermediate said openings and integral with the leaf for causing interlocking engagement between the same and the adjacent leaf.

7. In a leaf for loose-leaf books, the combination with a leaf portion proper, of a stub portion, openings therein for engagement with the filing-posts, depressions on one face of said stub portion, raised portions on the opposite face thereof, said depressions and raised portions being in alignment with the before-mentioned openings and arranged to interlock with corresponding depressions and raised portions in the adjacent leaf.

In testimony whereof I have hereunto affixed my signature in the presence of witnesses.

CHARLES E. BROADWELL.
